UNITED STATES PATENT OFFICE.

MAHLON L. DUNBAR, OF AKRON, OHIO.

SPARK-INTENSIFIER.

1,326,036.

Specification of Letters Patent. Patented Dec. 23, 1919.

Application filed March 16, 1918. Serial No. 222,954.

To all whom it may concern:

Be it known that I, MAHLON L. DUNBAR, a citizen of the United States, residing at Akron, in the county of Summit and State 5 of Ohio, have invented new and useful Improvements in Spark-Intensifiers, of which the following is a specification.

This invention relates to spark intensifiers, the object in view being to produce a 10 simple, cheap and effective device capable of being attached to any spark plug for the purpose of materially intensifying and enlarging the spark delivered in the gap of the plug, the device being also valuable for 15 the purpose of rejuvenating a spark plug which has become foul and ineffective and requires cleaning, the device of this invention being applicable quickly and readily to such a plug and thereby avoiding the 20 necessity of cleaning such plug on the road.

A further object of the invention is to produce a device of the character referred to in which the parts are so constructed and combined that they are interchangeable and 25 admit of easy and quick assembly.

Another object of the invention is to so construct and combine the several parts of the device that the spark gaps may be accurately adjusted so that the two gaps will 30 be exactly equal, this being important in order to intensify the spark.

With the above and other objects in view, the invention consists in the construction, combination and arrangement of parts, as 35 herein described, illustrated and claimed.

In the accompanying drawings:

Figure 1 is a side elevation of the device.

Fig. 2 is a diametrical section through the same.

Fig. 3 is a cross section on the line 3—3 of Fig. 2.

Fig. 4 is a detail perspective view of the intermediate electrode holder and head spacing member, showing the intermediate 45 electrode.

Fig. 5 is a diametrical section through the same.

The spark intensifier, in the preferred embodiment thereof, comprises a pair of heads 50 1 of any suitable non-conducting material, the same being arranged at opposite sides of a cylindrical housing 2 which is clamped between the heads 1 and together with said heads forms a spark chamber. The cylindrical housing 2 is preferably constructed of transparent material, such as glass, in order 55 that a person may observe the sparks as they cross the gaps in said chamber.

The heads 1 are rabbed in their inner faces as shown at 3, to receive the ends of 60 the housing 2 and also to receive screens 4 of fine meshed wire fabric, such as miner's gauze, said screens being clamped tightly between the edges of the housing 2 and the heads 1. The gauze screens 3 and 4 provide 65 for a circulation of air through the spark chamber, the heads 1 being formed with air ports 5 which admit air to and from said chamber, the gauze screens, however, preventing the admission of explosive vapor or 70 fume to the chamber and consequently, preventing ignition thereof by the sparks formed in said chamber. The heads 1 are held in clamping engagement with the housing 2 by means of tie bolts 6 which are inserted through the heads and arranged outside of the housing 2, as shown in the drawings.

The heads 1 are bored and threaded to receive a pair of electrodes 7 and 8, said electrodes being threaded through said bores for the purpose of adjustment and being securely held when properly adjusted by lock nuts 9 and 10. 11 designates a clamping nut to enable one of the current 85 wires to be attached to the electrode 8.

The inner ends of the electrodes 7 and 8 are preferably rounded as shown at 12 and interposed between such inner rounded ends of said electrodes is an intermediate electrode 13 preferably of spherical formation. The electrode 13 is contained in a holder 14 having a substantially annular body portion and oppositely extending projections or studs 15 imparting to said holder a castellated formation, the extremities of the projections 15 bearing against the heads 1 as shown in Fig. 2. The projections 15 are of such length that the maximum length of the holder 14 is slightly greater than the corresponding length of the casing 2, so that the holder 14 will sustain the pressure of the heads 1 and prevent the fracture of the casing 2 when the parts are securely clamped together. The holder 14 is composed of any 95 suitable non-conducting material, and is molded or otherwise formed around the intermediate electrode 13. If desired, the electrode 13 may have projections 16 thereon received in corresponding sockets in the holder 14 as shown in Fig. 5, although this is not 100 essential but the expedient may be resorted

105
110

to, to prevent any possibility of dislocation of said electrode 13.

In order to obtain the best results and insure the formation of an intensified spark, the electrodes 7 and 8 are adjusted so as to leave gaps of equal width between each electrode 7 or 8 and the intermediate electrode 13. One of the electrodes 7 is preferably formed with an eye 17 to enable the same to be placed over the binding post or projecting end of the power electrode or spark plug. In applying the device to a spark plug, the usual nut is removed from the plug and the eye 17 is placed over the binding post or power electrode of the plug and the nut then reapplied, thus clamping the device to the plug. The current wire is then clamped between the nuts 10 and 12. All parts of the device are made interchangeable, so that a broken part may be easily replaced at small cost. The necessary ventilation is provided for in the sparking chamber, preventing any possibility of an explosion occurring therein.

25 I claim:

1. In a device of the class specified, the combination with a sparking chamber including spaced heads, a pair of longitudinally aligned electrodes having adjustable engagement with said heads and movable toward and away from each other, an intermediate electrode interposed between the inner adjacent ends of the first mentioned electrodes and an insulated holder for said intermediate electrode provided with means for engaging said heads.

2. In a device of the class specified, the combination of a sparking chamber including heads, a pair of longitudinally aligned electrodes having a threaded and adjustable engagement with said chamber toward and away from each other, an intermediate electrode interposed between the inner adjacent ends of the first mentioned electrodes, an insulated holder for said intermediate electrode, said electrode holder also forming a spacing member for the heads of said chamber, said heads being separable, and means for clamping said heads in place.

3. In a device of the class specified, a 50 sparking chamber comprising a pair of heads of non-conducting material, a cylindrical peripheral wall clamped between said heads, oppositely arranged electrodes having a threaded and adjustable engagement 55 with said heads, of an intermediate electrode positioned between the inner ends of said electrodes, and a combined holder and spacing member of non-conducting material supporting said intermediate electrode and 60 clamped between said heads.

4. In a device of the class specified, a 65 sparking chamber comprising a pair of heads of non-conducting material, a cylindrical peripheral wall clamped between said heads, oppositely arranged electrodes having a threaded and adjustable engagement 70 with said heads, an intermediate electrode positioned between the inner ends of said electrodes, a combined holder and spacing 75 member of non-conducting material supporting said intermediate electrode and clamped between said heads, said heads being formed with ventilation ports, and gauze screens clamped between the peripheral wall of the 80 chamber and the heads of said chamber and extending across said ventilation ports.

5. In a device of the class specified, the combination of a spark chamber, a sectional housing inclosing the same and comprising 80 oppositely arranged heads, oppositely arranged electrodes threaded through said heads, an intermediate electrode, and a holder for supporting the intermediate electrode between the first named electrodes 85 with the gaps between the electrodes equal.

6. A device for intensifying the sparks across the sparking points of spark plugs, comprising separated heads, an electrode carried by each head, an intermediate electrode, and means for supporting the intermediate electrode between the first mentioned electrodes with the air gaps equalized, said means holding the heads in spaced relation. 95

In testimony whereof I affix my signature.

MAHLON L. DUNBAR.
